UNITED STATES PATENT OFFICE

EDWIN BURHORN, OF HOBOKEN, NEW JERSEY

COOLING TOWER

Application filed May 31, 1929. Serial No. 367,594.

This invention is a novel cooling tower, that is to say, an apparatus of the class by which air currents are brought into contact with the water to be cooled, the latter being caused to pass by gravity through the tower while subjected to the cooling influence. The invention is shown embodied in a tower preferably using natural air currents, but could be employed with other types of cooling tower, for example using forced draft. Further, the invention is shown as applied to the class of cooling tower in which the descent of the warm water is interrupted and delayed by means of one or more structures or cooling decks arranged at various points in the height of the tower for preventing a too rapid passage of the water, but is available in a simple tower having little or no means of delay of descent from the top of the collecting pan at the bottom.

The main object of the present invention is to improve the initial distribution of the water in a cooling tower whereby to increase the cooling efficiency. Other objects and advantages of the invention will appear in the hereinafter following description or will be apparent to those skilled in the art.

To the attainment of the above referred to objects and advantages, the present invention consists in the novel combination, arrangement, constructions, devices and other features shown or described herein.

In the accompanying drawings showing one form or embodiment of the invention, Fig. 1 is a side elevation of a cooling tower embodying my invention; and Fig. 2 is a vertical transverse sectional view on line 2-2 of Fig. 1.

In constructing my improved cooling tower, a plurality of upright corner-posts 10, formed of suitable material, are mounted above a suitable supporting base 11, and are interconnected by cross-bars or channel members 12 and 13 which are arranged in pairs at different heights, and the channel members 13 being disposed at right angles to the members 12. Along each of the four sides of the frame as thus constituted may be a series of louvers of any ordinary or preferred type, such louvers being omitted from the

drawings because they form no essential part of the present invention. A disclosure of louvers is to be found in my prior Patent No. 1,443,974 of February 6, 1923, which may be referred to for details.

The distributing vessel to be described below, or several of them in series, may be used with or without intermediate cooling decks, and give an effective shower and cooling; but as a system of decks is usual these are illustrated and will now be described.

The several pairs of cross-bars or channel members 12 and 13 constitute supports for the successive cooling decks 14, 15 and 16, arranged in superimposed relation. Any number of such decks may be employed dependent upon the capacity of the tower, three being shown. Furthermore, the specific construction of the decks may be varied as desired, and may comprise simple slats, or be omitted altogether. Those in the drawings each comprise a plurality of narrow troughs 17 disposed side-by-side, with their opposite ends resting on the respective cross-bars 12 or 13, as the case may be, and held firmly in position by clamping rods 18 and eye-bolts 19. The troughs of each deck are held in spaced relation by means of collars or spacing blocks 20 on the clamping rods, making possible the overflow of water between the adjacent troughs.

The troughs 17 in alternate decks extend transversely with reference to those immediately above and below them. The upper longitudinal edges of each of the troughs are provided with notches 21 so that the accumulating water in each trough will pass out from the same at designated points in relation to the distributing members of the deck beneath. For example each notch may be in substantially central vertical alignment with one of the troughs of the deck beneath whereby to discharge directly into the same. Thus as the water descends through the cooling tower, it will be intercepted at each deck whereby to retard its flow, and will be redistributed uniformly at each deck.

At the top of the tower is the distributing vessel 23 characterizing this invention, and which may be used singly or in sets. While

its form may be varied it is illustratively shown in the form of an open trough or tank of rectangular form which receives the water to be cooled from a standpipe 24. The tank 23 preferably extends crosswise with relation to the troughs 17 of the first deck 14, and is spaced above the same a substantial distance. Each side wall of the trough or vessel 23 along its length is provided with a series of 10 discharge apertures 25 arranged at different depths, the apertures for example being arranged as shown in several inclined rows. The several apertures of each series are arranged not only at different levels but also 15 preferably in vertical alinement with the several troughs 17 of the deck 14, when such a deck is used.

By virtue of the fact that the successive apertures 25 of each series are at different 20 depths in the vessel, the resultant head of water will be different and will cause the water to be projected to different lateral distances from the sides of the tank. For example, as shown in Fig. 2, the water discharged from the upper holes of each series 25 will fall rather abruptly, as indicated by the dotted lines A, while the water issuing from the intermediate level will be forced further out from the sides of the tank, as represented 30 by the dotted lines B, and the water flowing from the lowermost apertures will be forced still further outwardly as shown by the dotted lines C. In this way the initial distribution of the water is spread out in a wide 35 cooling area, taking better advantage of the cooling air currents at that portion of the tower. In some cases the same principle could be employed at a distributing level or deck below the initial distribution point.

40 Normally the vessel or tank is intended to be kept full of water, the supply equaling or exceeding the distribution through the apertures 25. Thus the level of water will be somewhat above the uppermost apertures 25, 45 so that the side wall apertures 25 may discharge in a constantly uniform manner. Any over-supply of water may be handled as follows. The upper edges of the tank are formed with overflow notches 26 which will 50 direct the overflow into certain of the troughs below.

55 As usual, a collecting pan 28 is disposed at the bottom of the cooling tower to receive the cooled water from the lowermost deck, and from which said water is conducted to a place of use through a drain pipe 29.

From the foregoing it will be seen that an 60 improved cooling tower has been provided, wherein is obtained an initial or other distribution of the water through a wider area or cooling zone than has been customary, and in a simple manner, resulting in a substantial increase in the efficiency of the cooling action. 65 The construction is simple, economical of

manufacture, and strong and durable in service.

The invention is susceptible of modifications in the details of construction and arrangement of parts within the principle of 70 the invention, and the invention is not intended to be limited to disclosed details except to the extent set forth in the appended claims.

75 What is claimed is:

1. In a cooling tower a distributing vessel having a closed bottom and upright sides, and along each side a series of discharge apertures arranged at different depths to cause the issuing streams to project to different lateral distances, and a cooling deck spaced therebelow comprising members located to receive and redistribute the several streams from the distributing vessel. 80

2. In a cooling tower having a frame and a plurality of superimposed cooling decks, water distributing means comprising a tank mounted on said frame above said decks, and having a plurality of discharge ports in its side at different levels, the respective ports at different levels being out of vertical alinement, and the deck therebelow having receiving troughs in alinement with the respective ports. 90

3. In a cooling tower of the class described, a support, a water distributing tank mounted on the support, and a redistributing deck below said tank, said redistributing deck comprising a plurality of narrow troughs disposed in side by side relation and extending 100 transversely with reference to the direction of the distributing tank, and the distributing tank being characterized by discharge apertures in its sides, each of said apertures being in vertical alinement with a different trough of the redistributing deck, and the aggregate of said apertures being insufficient to deplete the full level of the tank under normal conditions. 105

4. In an atmospheric cooling tower, the 110 tower frame, having substantial height and open sides whereby to admit the lateral passage of natural air currents, and at the top of the tower a distributing vessel having along its wall a system of laterally directed discharge apertures spaced longitudinally and at varying depths to produce a system of laterally projected water jets resulting in vertical streams spaced apart in both horizontal dimensions. 115

5. In a cooling tower a top cooling deck comprising a system of deck members adapted to receive water and cause it to descend in longitudinally and transversely distributed condition, in combination with a relatively narrow distributing vessel spaced above said deck and having an imperforate bottom but along each lateral side a series of discharge apertures arranged at different depths to cause the issuing streams to project laterally 125 130

outward to different distances, for distribution upon the deck members of the cooling deck.

6. In a cooling tower having a frame and
5 a plurality of superimposed cooling decks,
of which the top deck comprises a series of
parallel deck members for receiving warm
water and redistributing it over the horizontal
width and length of the deck, water dis-
tributing means comprising a trough mounted
10 on said frame above said top deck, and
having a closed bottom and at each lateral
side means for discharging water laterally
at different levels, whereby to produce a sys-
tem of separate jets to pass to the deck mem-
bers of the top deck and descend in longitudi-
nally and laterally redistributed condition.

In testimony whereof, this specification has
been duly signed by:

20 EDWIN BURHORN.
